FIG. 5.

UNITED STATES PATENT OFFICE

LLOYD G. COPEMAN, OF FLINT, MICHIGAN, ASSIGNOR TO COPEMAN LABORATORIES COMPANY, OF FLINT, MICHIGAN, A CORPORATION OF MICHIGAN

REFRIGERATING APPARATUS

Application filed February 12, 1932. Serial No. 592,572.

This invention relates to refrigerating apparatus, and has to do particularly with a simple manually operated manually controlled device for the local application of cold. 5 Heretofore, in the medical and surgical arts much use has been made of cold packs and more particularly small tubes of various kinds for the local application of heat or cold to both internal and external portions of the 10 human body. Even with the application of cold packs to external portions of the body, the results have been far from desirable because of inability to maintain a constant temperature and more especially because of inability to maintain a sufficiently low temperature. 15 This is also true in the treatment of certain portions of the nose and throat.

It is the object of the present invention to provide a refrigerating device which can be 20 applied to any part of the body, either externally or internally, and which device can be formed into any size or length whereby heat may be abstracted from any portion of the body and the temperature of that portion of 25 the body maintained constant for any length of time desired. More specifically, the present invention embodies a container which may be of any form suitable to the application to external parts of the body or which may be 30 in the form of a specially shaped tube for cooling or freezing internal portions of the body, said container being provided with passageways for the circulation of refrigerant. The temperature at certain points or 35 certain parts of the container whatever may be its shape, may be varied by varying the thickness of certain parts of the container wall. To keep this device at a constant temperature and to obtain any temperature desired, I preferably utilize a CO₂ refrigerating device of the type wherein the circulation of refrigerant is effected by the pressure developed during the evaporation of a block 40 of CO₂. Other features of the invention will be more clearly brought out in the specification and claims.

In the drawing:

Fig. 1 is an elevation, partly in section, of 50 one form of CO₂ refrigerating device con-

nected up with my heat absorbing or what might be termed cold applying unit.

Fig. 2 illustrates a modification wherein the cold applying unit is embodied in the 55 form of a tube.

Fig. 3 is a sectional view taken on line 3—3 of Fig. 2.

Fig. 4 is a sectional view of a further modification of the cold applying unit wherein such unit is shown preferably in the form of 60 a cold pack.

It will be understood that the medicinal or surgical heat exchange unit may take many different forms and may be made of many different materials in accordance with 65 the particular use to be made of the unit. For the purposes of the present invention, these heat exchange units will be called cold applying units. About the only limitation in the design of the cold applying unit is that it 70 should contain circulating and/or distributing passageways.

In Fig. 1 I have illustrated a cold applying unit which may be generally designated 2 and which consists of a metallic cap member 3 75 having an inwardly extending partition forming portion 4. A bag 5 of any suitable material such as rubber or rubberized fabric may be attached to the cap portion 3. The attaching of the bag 5 to the cap portion will 80 form a cold applying unit having a circulating conduit 6.

The partition portion 4 may contain a thermostatic unit 7 which may be of the pressure bulb or any other suitable type. A 85 suitable control gauge 8 may be used for indicating or controlling the effective operating temperature of the thermostat 7. Suitable valves 9 and 10 may be used for controlling the flow of refrigerating medium into and 90 from the cold applying unit.

It will be obvious that the use of a volatile refrigerant for a device of this kind would 95 hardly be practical and certainly would be dangerous and any mechanical refrigerating system whatever the method of heat transmission, would not only be expensive but its lack of mobility would make its use impractical in many instances. To make the medicinal or surgical cold applying unit safe at all 100

times and to make its use simple and practical regardless of the particular place of use, I preferably use solid CO₂ as illustrated at 11 as the refrigerating medium and in making use of this solid CO₂ I provide a container 12 sealed except for a relief valve 13 and a thermostatically controlled valve 14.

The relief valve 13 may be set to maintain any desired pressure within the container 12 and in all instances the pressure maintained within the container by the relief valve will be low enough as to prevent the formation of liquid CO₂ within the container. For practical purposes I have found that the relief valve 15 may be set to maintain approximately ten pounds pressure within the container 12.

A suitable conduit 15 connects the control valve 14 with the inlet valve 9 of the container 2.

20 In normal operation, the container 12 having been charged with solid CO₂, the valve 14 may be so regulated as to maintain, in combination with the thermostatic control member 7, the proper circulation of evaporated CO₂ gas to maintain the desired temperature within the cold applying unit. The nature of such thermostatic control means will be understood by those skilled in the art and, regardless of whether the thermostatic member 7 is of the pressure or temperature type, it will be understood that the valve 14 will be open or closed to provide proper circulation of the CO₂ gas to maintain a predetermined temperature within the container 2.

35 In the modification illustrated in Fig. 2, the cold applying unit is in the form of a rubber tube having a partition 16 for defining a circulating passageway. In this modification the walls of the tube may be made of different 40 thicknesses as at 17 and 18 so as to vary the rate of heat exchange at certain localized points as desired.

In the modification illustrated in Fig. 4 I have shown a cold pack somewhat similar to 45 the unit shown in Fig. 1 except that the partitions are formed integral with the unit as at 19. Such unit may be formed of rubber and to maintain any desired temperature a thermostatic unit 20 may be secured to a wall 50 thereof. In this case temperature control is obtained preferably by varying the circulation of the CO₂ gases as above set forth in the description of Fig. 1.

The conduit 15 leading from the valve 14 to 55 the cold applying unit may pass through the container 12 or directly from the valve 14 to the inlet valve 9 of the cold applying unit. While in normal operation all of the CO₂ gas passing through the unit 2 will pass to the 60 atmosphere through the outlet valve 10, it will be obvious that whatever might happen in the system the pressure throughout such system cannot rise above that determined by the relief valve 13. Accordingly, the walls of 65 the cold applying unit may be relatively

thin and flexible without any danger of bursting and in case there should be leakage at any point no harmful results could occur because of the nature of the refrigerant used.

What I claim is:

70 1. A refrigerating system for the application of cold in medicinal and surgical uses, comprising a cold applying unit, a circulating conduit within said unit, a container for receiving a charge of solid CO₂, means for conducting the vaporized CO₂ gases into the circulating conduit of the cold applying unit, and means for controlling the escape of gas from said container to maintain a relatively small amount of pressure in the system.

75 2. A refrigerating system for the application of cold in medicinal and surgical uses, comprising a cold applying unit, a circulating conduit within said unit, a container for receiving a charge of solid CO₂, means for conducting the vaporized CO₂ gases into the circulating conduit of the cold applying unit, means for controlling the escape of gas from said container to maintain a relatively small amount of pressure in the system, and thermostatically controlled means for regulating the supply of CO₂ gas to and through the cold applying unit to maintain the desired 80 temperature therein.

85 3. A refrigerating system for the application of cold in medicinal and surgical uses, comprising a cold applying unit having at least a portion of its walls of relatively thin 90 flexible material, a container for receiving a charge of solid CO₂, means for controlling the escape of said CO₂ gas from said container, means for conducting at least a portion of the CO₂ gas through the cold applying unit, and means for maintaining a relatively low pressure throughout the system.

100 4. A refrigerating system for the application of cold in medicinal and surgical uses, comprising a cold applying unit having at least a portion of its walls of relatively thin 105 flexible material, a container for receiving a charge of solid CO₂, means for controlling the escape of said CO₂ gas from said container, means for conducting at least a portion of the CO₂ gas through the cold applying unit, and means for controlling the amount of CO₂ gas circulated through the 110 unit to regulate the transfer of heat units to the portion of the body to which the heat 115 is applied.

120 5. A refrigerating system for the application of cold in medicinal and surgical uses, comprising a cold applying unit formed at least in part of flexible elastic material, a container for receiving a charge of solid CO₂, means for controlling the circulation of at least a portion of the vaporized CO₂ gases through the cold applying unit, and means for maintaining the vaporized CO₂ at a relatively low pressure throughout the system.

6. A refrigerating system for the application of cold in medicinal and surgical uses, comprising a cold applying unit formed at least in part of rubber, a container for receiving a charge of solid CO₂, means for controlling the circulation of at least a portion of the vaporized CO₂ gases through the cold applying unit, and means for maintaining the vaporized CO₂ at a relatively low pressure throughout the system.

7. A refrigerating system for the application of cold in medicinal and surgical uses, comprising a cold applying unit formed at least in part of flexible elastic material, means for creating and supplying refrigerant in the form of CO₂ gas to said unit, said unit being so fabricated as to provide passageways therein for circulating said gas, and means for regulating the amount of CO₂ gas supplied to said unit to control the temperature thereof.

8. A refrigerating system for the application of cold in medicinal and surgical uses, comprising a cold applying unit formed of flexible elastic material, a circulating conduit formed within said unit, a container for receiving a charge of solid CO₂, means for supplying vaporized CO₂ gas to said container, a portion of the wall of said unit being of varying cross section so as to accelerate the heat transfer between a portion of the body and said cold applying unit at one or more localized points.

In testimony whereof I affix my signature.
